UNITED STATES PATENT OFFICE

157,865

POWER-DRIVEN TWO-WHEELED VEHICLE

Terence Gordon Hare, Saginaw, Mich.

Application February 9, 1948, Serial No. 144,370

Term of patent 14 years

(Cl. D90—8)

To all whom it may concern:

Be it known that I, Terence G. Hare, a subject of the King of Great Britain, residing at Saginaw, county of Saginaw, and State of Michigan, have invented a new, original, and ornamental Design for a Power-Driven Two-Wheeled Vehicle, of which the following is a specification, reference being had to the accompanying drawing, forming part thereof.

In the drawing:

Figure 1 is a perspective view of a power-driven two-wheeled vehicle, showing my new design.

Figure 2 is a perspective view of the opposite side thereof.

I claim:

The ornamental design for a power-driven two-wheeled vehicle, as shown.

TERENCE GORDON HARE.
